UNITED STATES PATENT OFFICE.

WILLIAM A. SMITH, OF EASTON, PENNSYLVANIA, ASSIGNOR TO INGERSOLL-RAND COMPANY, OF JERSEY CITY, NEW JERSEY, A CORPORATION OF NEW JERSEY.

THROTTLE-VALVE FOR DRILLS.

1,370,061.

Specification of Letters Patent.

Patented Mar. 1, 1921.

Application filed March 23, 1918. Serial No. 224,333.

To all whom it may concern:

Be it known that I, WILLIAM A. SMITH, a citizen of the United States, residing at Easton, in the county of Northampton and 5 State of Pennsylvania, have invented a certain new and useful Improvement in Throttle-Valves for Drills, of which the following is a specification.

This invention relates to percussive tools, 10 and in particular to a throttle valve for self rotating hammer drills.

In many forms of percussive or hammer drills a motor is provided which, being supplied with motive fluid of the same kind as 15 supplied to the percussive element, produces rotation of the drill or other mining implement. This necessitates a throttle valve to vary and control the supply of motive fluid to the percussive and rotating elements of 20 the drill, which elements take varying portions of fluid, depending upon the class of rock being drilled.

The objects, therefore, of the present invention are to provide a throttle valve for 25 hammer drills or other rotating rock drills which will control the supply of fluid to the drilling and rotating mechanism; that will permit the regulation of fluid to the rotating mechanism while the drill is in operation, and will cut off the supply of fluid to 30 the rotating mechanism when the drill is stopped. Another object is to permit the valve for varying the supply of fluid to the rotating member to be contained within the 35 throttle valve and to be moved bodily thereby so that when the throttle valve is opened the valve for supplying the rotating mechanism will not require readjustment but will be brought back to the same place relatively 40 to its port to which it was previously adjusted.

With these and other objects in view, my invention consists in the features of construction set forth in the following specification and illustrated in the accompanying drawings.

In the drawings annexed hereto and forming a part hereof:

Figure 1 shows a longitudinal view of the 50 drill with the throttle valve shown in section;

Fig. 2, a longitudinal view of the complete tool in section;

Fig. 3, a view in cross section of the 55 rotating motor;

Fig. 4, a cross section through the throttle valve taken on the line 4—4 of Fig. 1;

Fig. 5, a view similar to Fig. 4, taken on the line 5—5 of Fig. 1.

Referring more particularly to the drawings, 1 shows the cylinder of a hammer drill having a throttle valve 2 made in accordance with the present invention. At 3 is shown the piston adapted to reciprocate within the cylinder 1, being supplied with 60 motive fluid through passages 4 to the various pressure areas of the piston 3. The drill rotating mechanism 5 comprises a geared motor which is supplied with motive fluid through the passage 6. It is the function of the throttle valve 2 to control the supply of fluid through the passages 4 and 6 in a manner presently to be described to vary the power and speed of the rotating motor.

The throttle valve 2 comprises a casing which is preferably made integral with the cylinder 1. This is bored to a taper from one end to the other, as is usual, and fitting this bored section is a hollow sleeve 7, rotation of which opens and closes passages to the ports of the drill. For this purpose the sleeve is provided with two ports 8 and 9 extending through the lateral face of the sleeve, as clearly shown in Fig. 1. The port 80 8 opens and closes communication with the passages 4 controlling the operation of the piston 3 while the port 9 opens and closes the passage 6 admitting fluid to the rotating motor 5. It is obvious that the speed and 85 power of the rotating motor 5 must be regulated for the different types and hardness of rocks in which the hammer drill is being used. This is accomplished by means of an independently operated valve placed within 90 the throttle valve 2 as shown at 10. Within the hollowed section of the sleeve 7 is placed the valve 10 having a portion tightly 95 fitting the inside of the sleeve 7 about the port 9 so that rotation of the valve 10 relatively to the sleeve 7 will open and close the port 9. This portion of the valve 10 is provided with flattened portions 11 permitting the passage of fluid past this portion of the valve and permitting it to enter the port 100 8, one edge covering or uncovering the port 9.

It will be seen from the description above that movement of the throttle valve 2 by means of its handle 12 will open and close 110

both ports, namely, 8 and 9. However, the auxiliary valve 10 within the sleeve 7 may be independently operated by means of its handle 13. This allows the valve 10 to be 5 adjusted so that just the proper amount of fluid enters the passage 6 to operate the rotation motor 5 at the proper speed and also avoids changing the position of the handle 13 of the valve 10 so long as the same condition of drilling exists, but this valve 10 may 10 be readily adjusted relatively to the main throttle valve 2 by slightly moving the handle 13 in relation to handle 12. Movement of the handle 12 controls both valves; 15 that is, closes or opens communication with passages 4 and 6, so that when the drill is shut down both the piston 3 and rotating motor 5 are stopped. When the drill is started, movement of the handle 12 to open 20 the passage 4 to fluid pressure also opens the passage 6, and this movement of valve 2 by means of handle 12 does not affect the position of valve 10 in relation to port 9, so that unless the handle 13 is moved relative to handle 12 the speed of the rotating 25 motor 5 is not affected and does not have to be adjusted each time the drill is started.

The passage 6 at the point where it joins the throttle valve 2 is enlarged, at 16, so 30 that the port 9 opens into this enlargement 16 of the passage 6 before the port 8 opens. This enables the rotating motor 5 to be started and brought up to speed before the piston 3 is started. A movement of about 35 forty five degrees of the handle 12 opens port 9 into passage 6 and a further movement of about forty five degrees of this handle opens the port 8 and passage 4, the passage 6 being still kept open. This is 40 clearly shown in Figs. 4 and 5.

At one end of the throttle valve 2 is the plug 14 and nipple 15, as is usual in this type of valve, through which fluid is supplied from an outside source to the space 45 within the sleeve 7.

In operation, the handle 12 is first moved to its open position, after which the handle 13 is adjusted relatively to handle 12 so that the rotating motor 5 is regulated to the speed desired. In shutting off the drill 50 the handle 12 is simply moved back to its closed position, which closes both ports 8 and 9. To start up the drill it is simply necessary to move handle 12 to its open position, which will also open port 9 to the 55 position to which it had previously been adjusted.

It is to be understood that while the present showing and description disclose only one specific embodiment of the present invention, other forms and modifications are included within the spirit and scope of the invention, as expressed in the appended claim.

What I claim is:

In a fluid operated percussive tool, the combination of a reciprocating motor, a rotation motor, and a throttle valve comprising a casing having a tapered bore provided with an inlet at the larger end and lateral supply passages leading to the said motors respectively, a hollow sleeve rotatable in said bore and having admission ports controlling said supply passages, a handle for operating said sleeve, an independently operated auxiliary valve within the said sleeve and movable therewith having a stem, and a plug provided with flattened sides, said plug controlling the admission port in the sleeve leading to the 70 rotation motor but permitting the passage of motive fluid from the said inlet in the casing past the plug and through the sleeve to the ports leading to the reciprocating motor and a separate handle for operating 75 said independent auxiliary valve.

In testimony whereof, I have hereunto set my hand.

WILLIAM A. SMITH.
